UNITED STATES PATENT OFFICE

2,064,700

ELECTROMAGNETIC DEVICE

Alexander Stein, Philadelphia, Pa.

Application June 18, 1935, Serial No. 27,254

6 Claims. (Cl. 175—345)

This invention relates to electromagnetic devices generally and, more particularly, to electromagnetic recording devices for use in telephone systems and the like. The device of this invention lends itself nicely to the recording or registering of telephone calls but it may be used in any instance where an electromagnetic recorder or register is desired. Moreover, the invention, or certain features thereof, is applicable broadly to the general field of electromagnetic devices.

One object of the invention is to provide a novel electromagnetic structure which is adapted to operate in any position and which is so constructed that the armature of the device will not stick or become inoperative regardless of the position of the device during operation.

Another object of the invention is to provide a novel electromagnetic structure which is composed of readily removable parts whereby the device may be completely disassembled for replacement of parts or for any other purpose.

A further object of the invention is to provide in an electromagnetic device a novel armature structure which is floatingly mounted so as to be freely operable at all times and which is free of contact with the electromagnet core.

A still further object of the invention is to provide a novelly constructed recording or registering device for telephone systems and the like, which device has the several features above mentioned and others set forth hereinafter.

The invention may be more clearly understood by reference to the accompanying drawing illustrating a specific embodiment, it being understood, however, that the invention is not limited thereby.

In the drawing:

Fig. 1 is a front elevational view of the device;
Fig. 2 is a side elevational view of the device;

Fig. 3 is an enlarged fragmentary sectional view illustrating the supporting structure more clearly;

Fig. 4 is a sectional view taken along line 4—4 of Fig. 2;

Fig. 5 is a sectional view taken along line 5—5 of Fig. 2;

Fig. 6 is an enlarged fragmentary sectional view illustrating more clearly the armature structure and mounting therefor;

Fig. 7 is a perspective view of an element of the armature structure;

Fig. 8 is a perspective view of a spring which may be employed in the armature structure; and

Fig. 9 is a perspective view of a bracket.

Referring to the drawing, the supporting structure of the device comprises a plurality of parallel rods 1 which are adapted to support the various elements in the manner described hereinafter. Preferably, there are four of the supporting rods 1 arranged as illustrated but it is within the scope of the invention to provide any desired number of these rods. The electromagnet comprises a winding 2 and an associated magnetic core 3, these elements being mounted between and secured to spaced supporting plates 4 having openings therein to accommodate the rods 1, as clearly illustrated in Fig. 3. The supporting plates 4 of the electromagnet unit are removably held in proper position upon the supporting rods 1 by sleeves 5 and 6 whose inner ends abut against the plates 4 and whose outer ends abut against end plates 7 of the device, as seen in Fig. 3. The sleeves 5 and 6 are adapted to fit snugly upon the supporting rods 1 and the end plates 7 are provided with apertures to accommodate the rods. The end plates may be secured upon the supporting rods in any suitable manner; for example, the ends of the rods may be threaded for the reception of fastening nuts 8.

In its specific adaptation as a recording device, the device comprises a conventional recorder or register 9 which may, for example, take the form of a lever-type Veede-Root register. As clearly illustrated in Figs. 1 and 2, the recorder or register 9 may be mounted upon brackets 10 having sleeve or collar portions 11 which are adapted to fit snugly upon the supporting rods 1. These brackets may be removably mounted upon two of the supporting rods and for convenience, the recorder or register 9 may be considered as being mounted upon the "front" of the device. The supporting brackets 10 may be removably fixed in proper position upon the supporting rods 1 by means of sleeves 12, 13 and 14 positioned as clearly illustrated in Fig. 3.

In order to obtain the required actuation of the recorder or register from a small movement of the electromagnetic armature, the lever system shown more clearly in Fig. 2 may be employed. The lever 15 extending from the recorder shaft may be connected by a link 16 to a lever 17 which may be pivotally connected to an extending lug 18 of a bracket 19 (see Fig. 9). Bracket 19 may comprise sleeve portions 20 fitting snugly upon the supporting rods 1 at the back of the device and removably fixed in position on the rods by means of sleeves 21 and 22. The lever 17 may be connected to the armature by means of a link 23. It will be understood that the

lever system may be modified and, if desired, levers may be provided on either or both sides of the device.

A very important feature of the invention is the structure and mounting of the armature structure 24. In accordance with the invention, the armature consists of a thin light-weight plate structure floatingly mounted upon the supporting rods 1. In the specific structure illustrated, there is provided a thin plate 25 formed of light-weight non-magnetic material, such as fibre, and having apertures or openings of such size as to accommodate the supporting rods 1 and the sleeves 6 positioned thereon, as shown clearly in Fig. 3. Thus, the thin light-weight plate 25 is slidably mounted upon the supporting rods. A cruciform magnetic element 26 (see Fig. 7) formed of thin sheet metal is disposed on one side of plate 25 and has the outer extremities of its arms secured to plate 25 by means of rivets or the like 27. The plate 25 is provided with a central opening 28 which is of slightly smaller dimension or area than the end of the electromagnet core 3, as shown in Fig. 6. The central portion of the cruciform magnetic element 26 is offset as at 29 and extends into the opening 28, as clearly shown in Fig. 6. To insure that the offset portion 29 will be maintained within the opening 28, leaf springs 30 (see Fig. 8) may be secured at one end to the plate 25 by the fastening elements 27. The free ends of the springs may be arranged so as to press the central portion of the cruciform element in the desired manner.

It will be seen that the offset portion 29 of the magnetic element of the armature is cooperatively arranged with the electromagnet core 3 and is adapted to be attracted thereby, but the portion 29 is prevented from coming into actual contact with the core because the opening 28 is smaller than the end of the core, as above mentioned. Therefore, when the device operates, the portion of the non-magnetic plate 25 about the opening 28 abuts against the core 3 and prevents contact of the portion 29 therewith. This eliminates any sticking tendency of the armature, which is inherent in devices wherein the armature contacts the magnet core, particularly after considerable usage. As the same time, the desired electromagnetic association between the armature and the core is maintained. Furthermore, by employing a thin light-weight non-magnetic supporting plate and by employing a thin magnetic element of reduced area, the weight of the armature unit is reduced to a minimum. The light-weight non-magnetic plate functions efficiently as a freely slideable supporting member for the armature structure and when formed of insulating material, this plate insulates the conductive part of the armature structure from the general supporting structure. The use of four supporting rods also insures smooth sliding action and prevents binding or sticking of the armature regardless of the position of the device. Moreover, the parts of the armature structure may be economically formed by stamping them from sheet material.

In order to urge the armature to its inoperative position, there are provided coil springs 31 interposed between the plate 25 and the adjacent plate 4 of the electromagnet unit. It will be seen that these springs will insure that the armature returns to its inoperative position regardless of the position of the device in any instance. It may be

noted also that the spring of the recorder or register will assist the springs 31.

It will be seen that the armature movement may be varied by modifying the lever system. The rods 1 and sleeves 6 are sufficiently long to permit of such variation. Moreover, the electromagnet unit and the recorder may be adjusted to any desired position along the rods 1 by employing sleeves of varying lengths.

The extremities of the electromagnet winding 10 may be connected to terminals 32 mounted upon the upper plate 4 of the electromagnet unit. Thus electrical connection to the device may be made simply by connecting to the terminals 32. There are also preferably provided contacts 34 mounted 15 upon the lower plate 4 of the electromagnet unit, which plate may be formed of insulating material, the contacts 34 being arranged for cooperation with two of the metallic fastening elements 27. Conductors 33 may be connected between contacts 34 and terminals 32. With this arrangement, it will be seen that when the device is actuated, the engagement of the elements 27 with the contacts 34 will place a shunt about the electromagnet winding, which shunt includes the 25 conductive element 26 of the armature. Thus, this element of the armature is made to serve this additional purpose.

Thus the device is adapted for the provision of a novel shunting arrangement when desired, 30 it being well known in the art that such a shunt is often desirable. It will be noted, also, that the device may be used as a relay by omitting the conductors 33 and connecting the circuit to be controlled to the contacts 34. Thus the device is 35 adapted for varied electrical association with other devices. Moreover, the mechanical movement of the device may be used in conjunction with other devices. Hence, the device is adaptable for mechanical or electrical cooperation 40 with other devices.

It will be understood that in its adaptation as a device for recording the number of telephone calls, the device may be connected to any suitable part of the telephone system in accordance with 45 the conventional methods.

Although the invention has been described with specific reference to the illustrated embodiment, it will be understood that various changes and modifications may be made while retaining 50 the inventive features set forth more clearly in the appended claims.

I claim:

1. An electromagnetic device, comprising an electromagnet having a core, an armature including a thin non-magnetic plate having an opening adjacent said core, and a magnetic member carried by said plate and having a portion extending into said opening for cooperation with said core, and supporting and guiding means for 55 said armature comprising a plurality of parallel rods slidably carrying said plate in cooperative relation with said electromagnet, whereby said device may be operated in any position.

2. An electromagnetic device, comprising an 65 electromagnet having a core, an armature including a thin non-magnetic plate having an opening adjacent said core, a magnetic member carried by said plate and having a portion extending into said opening for cooperation with 70 said core, and spring means maintaining said portion within said opening, and supporting and guiding means for said armature comprising a plurality of parallel rods slidably carrying said plate in cooperative relation with said electro- 75

magnet, whereby said device may be operated in any position.

5. An electromagnetic device comprising a supporting framework comprising a plurality of parallel rods and transverse elements removably securing said rods together in a unitary assembly, an electromagnet, supporting end plates for said electromagnet having openings for reception of said rods, means comprising spacer sleeves for 10 maintaining said plates in proper position on said rods between said transverse elements, and an armature slidably carried by said rods in cooperative relation with said electromagnet, whereby said device may be operated in any position.
15. 4. An electromagnetic device, comprising a supporting framework comprising a plurality of parallel rods and transverse elements removably securing said rods together in a unitary assembly, an electromagnet having a core removably supported on said rods, and an armature slidably carried by said rods in cooperative relation with said electromagnet, said armature comprising a thin non-magnetic plate slidably carried by said rods and having an opening adjacent said core, 20 and a magnetic member carried by said plate and having a portion extending into said opening for cooperation with said core.

5. An electromagnetic device, comprising an electromagnet having a core, an armature including a thin non-magnetic plate having an opening adjacent said core, a cruciform magnetic member carried by said plate and having a central portion extending into said opening for cooperation with said core, and a plurality of leaf springs carried by said plate and arranged to press said portion into said opening, and supporting and guiding means for said armature comprising a 10 plurality of parallel rods slidably carrying said plate in cooperative relation with said electromagnet, whereby said device may be operated in any position.

6. An electromagnetic device comprising a supporting framework including a plurality of parallel rods, an electromagnet, supporting means for said electromagnet having openings for reception of said rods, means comprising spacer sleeves for maintaining said supporting means in proper 20 position on said rods, and an armature slidably carried by said rods in cooperative relation with said electromagnet, whereby said device may be operated in any position.
